UNITED STATES PATENT OFFICE.

JAMES L. BOYD, OF LA PORTE, INDIANA.

BURIAL APPARATUS.

SPECIFICATION forming part of Letters Patent No. 624,905, dated May 16, 1899.

Application filed May 7, 1898. Serial No. 680,010. (No model.)

To all whom it may concern:

Be it known that I, JAMES L. BOYD, a citizen of the United States, residing in La Porte, in the county of La Porte and State of Indiana, have invented a new and useful Improvement in Undertakers' Burial Apparatus, of which the following is a specification.

This invention relates to the construction of apparatus for undertakers' use in lowering caskets into the graves.

My object therein has been to provide a very light and portable form of apparatus which can be carried in the hearse or other vehicle and be erected and put in operative condition at the grave in a very short time and as quickly taken down and removed.

The invention consists in the novel construction of the apparatus and in the novel construction and combinations of devices and parts of devices hereinafter fully set forth.

In the accompanying drawings, Figure 1 is a side elevation, and Fig. 2 an end elevation, of the apparatus as it appears when erected and ready to be put into service. Fig. 3 shows the apparatus with the struts or legs folded. Fig. 4 is a partial longitudinal section. Fig. 5 is a cross-section. Fig. 6 is a detail sectional view of the hook for attaching the ends of the straps placed around the casket. Figs. 7 and 8 are details of a modification.

In said drawings, A represents a casket or the usual box in which the same is placed ready to be lowered by the apparatus, B B being the leather or canvas straps usually passed under the box or casket. One end of each strap is provided with a loop B', and the other end is securely held by a buckle B'', attached to the end of the windlass-ropes C.

The main feature of my apparatus consists of an exceedingly portable windlass adapted to be readily erected at the grave and readily removed, and it preferably consists of a windlass composed of sections D of metal pipe suitably united together—as, for instance, by a coupling-sleeve D' and folding legs or supports E E, such supports having sleeves E', in which the windlass may be revolved. At least one, and possibly both, of the sleeves E may be adjustable upon the windlass, so that at least one pair of the legs may be moved toward or from the other pair to adapt the apparatus to use with caskets of different

lengths. The windlass-ropes are each secured to rings C', made fast to the windlass by set-screws C'' or other suitable devices, and for the purpose of making the apparatus adjustable to different lengths one or both of these rings are preferably made adjustable to different points along the windlass.

The coupling-sleeve D' is made fast to one section of the windlass by brazing or otherwise and splined to the other, as shown at D'', and the set-screw D''' serves to prevent the splined section from pulling out of the sleeve. Of course it will be understood that the windlass may be made in one piece instead of two; but that would render it unhandy to carry about, and hence I prefer the sectional windlass.

The legs E are all pivoted upon pivots E'', supported in a swinging head E''', pivoted to a projection E'', depending from the sleeve E', by means of the pivot E'', this being the construction employed for the legs at each end of the windlass, and it permits each pair of the legs to be folded closely together and then swung into position parallel with the windlass, as seen at Fig. 3.

At one or both ends an operating device—such, for instance, as the hand-wheel F—is applied to the windlass, and by means thereof the windlass may be turned to lift the casket sufficiently to permit the removal of the cross-pieces, which are laid across the grave and support the casket, and then serve as a means for controlling the windlass while the casket is being lowered. Instead of the hand-wheel one end of the windlass may be provided with gearing, such as that shown at Figs. 7 and 8, whereby to operate and control it. This gearing may consist of the gear G, secured to one end of the windlass, and a small gear G', meshing with gear G and having bearings in the side of the inclosing case G'' and being operated by a crank or hand wheel G'', attached to its shaft. If desired, a braking-strap G'', passing around the hub of the gear G' and tightened by a lever G'', may be employed to control the windlass during the lowering operation.

Where the casket is heavy, the windlass may be supported at its center by means of a semicircular bearing H and legs H', applied to said bearing at each end thereof, the legs rest-

ing upon the ground at each side of the grave. These legs are preferably hinged to heads H², so they may be folded together, and said heads are attached to the bearing in any suitable way, either detachably or permanently, as preferred.

It is desirable that the straps B should be secured together at their ends in such manner as to insure their being automatically disengaged as soon as the casket is lowered. For this purpose I pass the end which is attached to the buckle, as already stated, through a forked or two-armed hook B³, having a cross-bar or bearing-surface at B⁴, against which the strap may frictionally bear, and a rearwardly-extending weight B⁵. The points of this hook engage the loop B', as seen at Fig. 6, and retain the hook in engagement so long as there is any strain upon the strap; but when the casket has been lowered and rests upon the bottom of the grave, so that there is no strain, the weighted end will fall to the position given in the broken lines, and such change in position allows the automatic disengagement of the hook and loop, so that the strap may then be drawn out by winding up the windlass.

In use the apparatus is placed over the casket and parallel therewith, as plainly illustrated. The legs H' brace the windlass in longitudinal directions, as is obvious, though this may not be necessary if the legs E are inclined slightly in proper directions. If desired, the sleeves E' and operating-wheels 35 may be removable from the windlass to facilitate packing of the apparatus in a small compass for carrying.

Instead of employing the spline D² and setscrew D³ for securing the end of the windlass-section D in the sleeve D' a key D⁴ may be

employed. This key should pass through both the sleeve and the windlass-section, and I prefer to make it long enough so that it may be secured in the opening through which it passes at both ends by the strap B³ or equivalent device, which will prevent it from falling out while in use. 45

The legs E of the windlass-supports are preferably armed at the bottom with sharp points E⁶, as shown at Fig. 3, to prevent them 50 from slipping.

I claim—

1. The combination with the windlass, of sleeves E' surrounding the windlass, and legs E pivoted to fold together and also to swing 55 into position parallel to the windlass, substantially as specified.

2. The combination with the windlass, of a sleeve E' surrounding the windlass at one end and adjustable along the same, legs attached 60 to said sleeve, and suitable supports for the other end of the windlass, substantially as specified.

3. The combination in burial apparatus of the windlass, supporting-legs, and a bearing 65 for the windlass, the supporting-legs being pivoted to the bearing so as to fold into position parallel to the windlass, substantially as specified.

4. The burial apparatus consisting of a 70 windlass made in separable parts, supports for each end thereof, and bearings carried by the supports, the supports being pivotally attached to said bearings so as to fold with the windlass, substantially as specified.

JAMES L. BOYD.
